IRON CORD HOLDER

Emil H. Blattner, Rochester, N. Y.

Application August 20, 1945, Serial No. 611,461

3 Claims. (Cl. 248—51)

1

This invention pertains to an iron cord holder and particularly to a pivotal type thereof.

An object of the invention is the provision of an improved and simplified iron cord holder capable of effectively maintaining an iron cord in a position elevated from an ironing board.

Another object of the invention is the provision of an iron cord holder capable of supporting constantly an iron cord in a position elevated from an ironing board while an iron is in use without developing or causing any sharp or injurious breaks in the iron cord.

A further object of the invention is the provision of an iron cord holder arranged to be urged resiliently away from the iron and being further arranged, at the option of the user, to be locked in a fixed position when the iron is not in use.

The above and numerous other objects will become apparent to those skilled in the art to which this invention appertains when the following description of an exemplified form of the invention is considered, together with the accompanying drawing wherein:

Figure 1 is a partial side elevational view of an ironing board having a form of the invention attached thereto.

Figure 2 is a partial plan view of the arrangement shown in Figure 1.

Figure 3 is an enlarged elevational view taken along the lines 3—3 of Figure 2, looking in the direction of the arrows.

Figure 4 is an enlarged elevational view taken along the lines 4—4 of Figure 2, looking in the direction of the arrows.

Figure 5 is a sectional view taken along the lines 5—5 of Figure 3, looking in the direction of the arrows.

Figure 6 is an enlarged view taken along the lines 6—6 of Figure 2, looking in the direction of the arrows.

Figure 7 is a sectional view taken along the lines 7—7 of Figure 6, looking in the direction of the arrows.

Referring now in detail to the drawing wherein like reference characters indicate like parts, the numeral 1 is employed to designate, in a somewhat general manner, an ironing board, commonly used as a domestic appliance upon which linens or the like are placed during an ironing operation. A typical electric hand operated or manoeuvred iron is indicated at 2, and the reference character 3 designates a usual insulated cord employed to carry electrical energy from a plug 4 to the electric iron. As an electric iron

2

is moved to and fro during an ironing operation the cord, if not otherwise accounted for, is drawn across the object being ironed and, as is commonly known, at times ruffles the object. Further, it is not uncommon for an iron cord to be soiled and thus if such a cord is permitted to come into contact with the object being ironed the object also may become soiled. To eliminate all these above mentioned undesirable conditions there has been provided an iron cord carrier, holder or support 5, the general arrangement of which is illustrated in Figures 1 and 2 of the drawings with enlarged views shown in Figures 3 through 7 to more clearly illustrate the details of construction and the arrangement of components. The iron cord holder comprises a clamp or anchor 6 preferably of cast form and being desirably removably secured to the ironing board at a far or distant edge thereof so as to be out of contact or at least interference with objects to be ironed. The anchor or clamp is formed by a substantially U-shaped clip or open housing 7 made up of a base plate 8 arranged to bear or rest upon the ironing board. Two transversely spaced side walls 9 rise from the lateral edges of the base plate and extend in parallel relation longitudinally of the ironing board. The side walls are joined along their rear vertical edges by a rear wall 10 which also merges with the base plate to form an integral part thereof. Spaced an appreciable distance below the clip is a horizontal arm 11 arranged transversely of the ironing board and underlying it a predetermined distance to present sufficient clearance between the clip and arm for the introduction therebetween of the ironing board and its usual pad or cover. The arm is joined to the base plate of the clip by a wall 12 with a reinforcing rib 13 starting at an upper extremity of one of the side walls to extend downwardly therefrom along that particular side wall, the wall 12 and terminating along the horizontal arm. The free extremity of the horizontal arm is formed as a tapped hub 14 through which there extends a rotatable element or thumb screw or winged bolt 15 with the latter being arranged to be manipulated so as to removably secure or bind the clamp or anchor to the ironing board.

Associated with the anchor is a standard, rod or extension 16 which may be formed of metal but preferably is made of wood because of its inexpensiveness and since wood contains qualities of lightness and non-conductivity. What might be considered a lower extremity 17 of the standard is positioned within and formed to be

neatly accommodated by the housing. The lower extremity of the standard is provided with a locked-in ferrule or metallic bushing 18, with this bushing being disposed in horizontal alignment with openings 19 in the side walls of the clip. Extending through the bushing and aligned openings is a pintle or pin 20 threadedly interlocked with one of the side walls to prevent an unwarranted displacement thereof and functioning as an axle about which the standard is arranged to pivot or as a pivotal connection between the rod and clamp. The lower extremity of the standard is bifurcated as at 21 and wound about the ferrule within the standard bifurcated end is a plurality of helices of a coiled torsion spring 22. The coil spring, anchored to the bushing, has one end thereof terminating in an arm 23 which acts against the clip base plate while the other end of the spring is angularly disposed as at 24 to act against the standard. By reason of this compact and novel arrangement the standard is at all times urged in a clockwise direction when viewing the showing in Figure 1, thereby drawing the iron cord in the same direction. When the standard reaches a predetermined extreme position, as illustrated by diagrammatic lines in Figure 1 of the drawing, this rotary movement of the standard is arrested by the latter becoming rested against the rear wall of the clip.

Spaced a given or optional distance along the standard from the bifurcated end is an eyelet 25 through which the iron cord is threaded to keep this end of the cord in assembled relation with the standard. From the eyelet the iron cord is strung along the standard toward the upper or free extremity 26 thereof. This extremity 26 of the standard is formed as an arcuate, circular, preferably fan-shaped terminal 27 which is grooved as at 28 in alignment with the iron cord so as to form a cradle. The iron cord rests within the groove and thus is held in a fixed position or prevented from becoming disengaged from the standard. In order to prevent the iron cord from creeping as well as assist in fixing the latter to the standard, there is provided a pair of bores 29 and into these bores are threaded legs 30 of U-shaped bracket or retaining means 31. The intermediate portion of the retaining means is provided with a preferably rubber or rubberized nipple 32 which bears upon or contacts the iron cord and the free ends of the legs are subsequently bent over as at 33 to lock the retaining means and standards together. By forming the free extremity of the standard with the arcuate portion it will be appreciated that the iron cord will roll over the top of the standard and thus kinks, injurious bends or sharp breaks cannot be formed in the iron cord at this juncture.

At times it may be desirous of folding the ironing board for storage in a cupboard or closet and to avoid the necessity of disconnecting the iron cord holder from the ironing board there is provided a hole or aperture 34 in both or one of the housing side walls. This hole is in normal misalignment with an aperture 35 in the standard. The apertures 34 and 35 are disposed on a common arc about the pintle so that by rotating the standard in a counterclockwise direction until it is parallel or substantially parallel with the ironing board the apertures 34 and 35 will come into alignment and by inserting any suitable pin or locking means (not shown) in the aligned apertures the standard will be maintained folded

down along the ironing board to facilitate storing of the latter.

From the above it will be noted that various changes and alterations may be made to the illustrated and described construction without departing from within the spirit of the invention and scope of the appended claims.

I claim:

1. In an iron cord holder, the combination of, 10 a clamp arranged for mounting along an edge of an ironing board and having an open housing, a standard having one end thereof bifurcated and positioned in said housing, pin means extending through said housing and bifurcated end for pivotally connecting said standard to said clamp, and a torsion spring journaled on said pin means within said bifurcated end; said torsion spring having one extremity thereof acting against said housing and another extremity acting against said standard for urging the latter in one direction about said pin means.

2. In an iron cord holder, the combination of, 15 a clamp arranged for mounting along an edge of an ironing board, a housing formed in said clamp, a standard arranged to movably carry said cord in a position elevated from said ironing board, a bifurcated end formed in said standard and being positioned in said housing, pin means pivotally connecting said standard to said housing, spring means extending around said pin means and arranged to urge said standard in one direction, and apertures in said standard and housing for the reception of holding means to maintain said standard in a fixed position substantially parallel to said ironing board.

3. In an iron cord holder, the combination of, 20 a clamp arranged for mounting along an edge of an ironing board, a U-shaped clip formed in said clamp, a standard arranged to movably carry said cord, a rounded end on said standard for preventing a sharp break in said cord as it leaves the standard, another end on said standard being positioned in said U-shaped clip, pin means extending transversely of said ironing board and through said last mentioned end and U-shaped clip for pivotally connecting said standard to said clamp, and spring means within said U-shaped clip acting against said clip and standard for urging the latter in one direction, and normally misaligned apertures in said clip and housing; said apertures being arranged to be aligned for the reception of holding means for holding said standard substantially parallel to said ironing board.

EMIL H. BLATTNER.
